PAPERHANGER'S FOLDING BOX AND
TABLE

Fred E. Edgren, Chicago, Ill.

Application November 4, 1942, Serial No. 464,549

3 Claims. (Cl. 164—78)

My invention relates to a folding paperhanger's box which, when in open and set-up condition, may be used as a paste table by the paperhanger in trimming wall paper and applying paste thereto; the box in collapsed or closed condition being adapted to receive the paperhanger's usual implements.

The paperhangers, in trimming wall paper, employ one section of the folding box in conjunction with a straightedge; the trimming of the cut strip of wall paper being performed within an inch or two from the outer longitudinal side of said table or box section, with the result that the table section or board soon becomes scored adjacent one longitudinal side and true or proper trimming of the wall paper can then no longer be accomplished.

As these tables are more or less expensive, it is essential that these folding boxes be so constructed that the comparatively narrow scored portion, namely a longitudinal marginal portion of the box, be readily removable for reversing and ultimate renewing. It is desirable in tables of this character to employ a grainless wood which, if used for the entire folding box, or for the entire top of one section of the folding box table, even though such top section was removable, would be too expensive, as the trimming operation is performed within a comparatively narrow longitudinal area of a few inches in width adjacent an outer longitudinal side or edge of the table-forming box.

My present invention contemplates forming the top of one of the box-sections of separate boards or elements having interengaging relation with each other along their contacting edges; the top being provided with surrounding rails whereby the boards are reinforced and held against warping and movement, preferably with one of the side rails mounted so that it may be moved out of holding relation with the adjacent top-board to permit the latter to be readily moved out of interengaging relation with its adjacent top-board and said first mentioned board reversed or replaced by a board of similar character. As the paper trimming operation is confined to a comparatively narrow marginal area, I propose providing the table-box at the outer longitudinal portion of one of the sections with a relatively narrow board of grainless wood, such as bass wood or other suitable material, thereby decreasing the cost of construction and maintenance.

The objects and advantages of my invention will all be readily comprehended from the fol-

lowing description of the accompanying drawings, wherein—

Figure 1 is a top plan view of my improved folding box or table.

Figure 2 is an enlarged cross-sectional view, taken on the line 2—2 of Figure 1 looking in the direction of the arrows.

Figure 3 is an enlarged side elevation as viewed on the line 3—3 of Figure 1 with an intermediate portion broken away and showing the outer side rail swung downwardly.

Figure 4 is a cross sectional view of a portion of one section of the folding box or table illustrating a modification.

15 Figure 5 is a bottom plan view of another modification of my improved box-table.

Figure 6 is an enlarged cross-sectional view taken on the line 6—6 of Figure 5 looking in the direction of the arrows.

20 Figure 7 is a similar view of a portion of one section illustrating the manner of removing the trimming strip.

As previously stated, my invention contemplates a paper hanger's paste box or trimming table of a collapsible or folding nature which may be supported by a suitable pedestal or trestle which may be hingedly secured to the inner or lower side of the box-table to fold within the box or be detachable therefrom. In the exemplifications of the invention, the box or table is shown preferably composed of wood and in the particular embodiment shown in the first three figures the box or table consists of two main sections 10 and 11 which are six or more feet in length and each of equal width to combinedly provide a table of width in keeping with the needs of the paperhanger.

25 In the illustration, Figure 1, for the sake of economy, the section 11 is intended to be employed for trimming while the section 10 constitutes the cover when the table is in closed or box-like form, although it will be understood that both sections may be of similar construction. The section 10 is shown with a single cover or top board 12 of preselected length and width, surrounded by a rectangular frame composed of the two side rails 13, 13 and the two end rails 14, 14, which, preferably, are of equal depth and may be intimately or immovably connected with each other and with the top board 12; the tops of the rails being arranged in the plane of the top or outer surface of the board 12, as shown at the right in Figure 2.

30 The section 11 is provided with a top consisting of boards 15 and 16 of equal length but of

different widths; the board 16 at the outer longitudinal marginal portion of section 11 constituting the paper trimming area of the box-table, which merely need be three or four inches in width, and preferably consists of grainless wood—such as basswood—or other suitable material; the other portion 15 of the top may consist of any suitable wood or material as it is not involved in the trimming operation. After repeated trimming operations, the strip or board 16 will become so scored that proper movement of the paper trimmer or cutter along a straight-edge is difficult and true trimming of the wallpaper made impossible. For that reason, the strip or board 16 is removably associated with the board 15 by means of the tongue-and-groove disposed throughout the contiguous longitudinal edges as shown at 17, see Figure 2. The top portions of boards 15, 16 of table section 11 are also surrounded by end rails 14, 14, inner side rail 13 and outer side rail 18, with the tops of the rails arranged in the plane of the top or outer surfaces of boards 15 and 16; the rails all being of equal depth and preferably of the same depth as the rails of the other section 10 in order that the combined depth of the rails of both sections 10 and 11, when in back-to-back or folded relation, will provide a box of sufficient depth to receive the paperhanger's usual tools as well as a suitable supporting trestle.

In order to permit the strip or board 16 to be easily removed when desired, the outer longitudinal side rail 18 is shown hingedly connected at 19, at its inner lower edge, to the reenforcing strips or cleats 20 disposed transversely along the lower sides of both sections 10, 11, the ends of the cleats 20, adjacent the inner side rails 13, 13, being bent downward against the rails into suitable grooves in the lower faces of the rails 13, with the adjacent ends of aligned cleats bent into hinge and pin receiving loops, as shown at 21, so as to permit back-to-back folding of the two sections with the lower edges of the rails of the two sections in superposed relation. The board 12 of section 10 and the board 15 of section 11 are preferably secured to the respective cleats 20 by small screws, as shown at 22, but which do not extend through the boards; the removable strip or board 16 preferably being unattached to the cleats which, however, provide transverse reinforcement or support for all the boards.

In order to properly hold the outer longitudinal edge of board 16, the outer side rail 18 is shown provided with a groove 23, adapted to receive the longitudinally disposed rib 24 on board 16, see Figure 2; the rib 24 being similar to the rib extending longitudinally at the opposite side edge of the board 16, as shown at 17 in Figure 2, thus enabling the strip or board 16 to be reversed end for end or turned over when occasion requires, to provide a new or scoreless paper trimming area.

One leaf of the hinge 19 may be suitably secured to the adjacent cleat 20, or it may consist of a portion of the cleat, while the other leaf of the hinge is preferably arranged in a groove in the lower edge of the side rail 18 and suitably secured thereto by a screw or screws, shown at 25 in Figure 2.

The movable side rail 18 is held in normal position by one or more bolts 26 disposed through registering holes in the rail 18 and the downwardly bent end of the cleat 20; the head of the bolt preferably being countersunk in the side rail, while the inner end of the bolt is shown

provided with a butterfly-nut, thus obviating the necessity for any special tools.

If, after considerable use, the top surface of strip or board 16 becomes too scored to permit accurate trimming to be performed, the paperhanger may quickly remedy the condition—without the necessity of discarding the table and the purchase of a new table—by simply releasing the butterfly nut and withdrawing the bolt 26 therefrom by releasing the rail 18 from the bent end of the cleat 20 which permits the side rail to swing into the downward position shown in dotted lines in Figure 2. In this position, the trimming board or strip 16 may be readily moved out of inter-engaging relation with the board 15 and either reversed end-for-end (as the beads or tongues 24 are similar along both side edges of the strip 16) to present the other longitudinal margin portion of the strip 16 toward rail 18, into the paper trimming zone, or the strip 16 turned upside-down to present the lower face in the trimming zone. As is apparent, these possibilities greatly enhance the useful life of the trimming table without increased expense.

With the hinge-forming ends at the down-turned portions of the cleats arranged in grooves on the lower surfaces of the side rails 13, 13 and 18, the lower faces of the two side rails may come into flush superposed relation and movable side rail 18 may come into flush superposed relation with the outer side rail 13 of the section 10 when the two sections 10 and 11 are folded back to back into box-like condition.

The table may be supported by any suitable trestle which, preferably, may be hingedly secured to the inner sides of the sections 10 and 11, as disclosed in Figure 2 where a part of a supporting leg is shown at 27 pivotally secured at 28 to an angle portion 29 of the cleat 20 and so disposed that it will fold against the inner or lower side of the table-section when the table is folded into box-like form.

In Figure 4, I show a modified form in so far as the outer side rail and the method of locking the trimming strip are concerned. In this form, the removable trimming strip 16^a, instead of being beaded along its longitudinal edges as in Figure 2, is provided with longitudinal grooves to receive the tongue or bead on the edge of main board 15^a, while the groove at the outer longitudinal side is intended to receive the round headed plug or screw 30 which preferably is threaded into a ferrule or screw threaded opening in the side rail 18^a, as shown at 31; the outer end of the plug or screw 30 being provided with a screw-driver receiving slit. In order to maintain the trimming strip in secure position, it will be understood that a number of screw plugs 30 are employed at intervals spaced lengthwise of the outer side rail 18^a. The side rail 18^a in this instance may be permanently secured to the end rails; and the tops of both table sections, if desired, may be provided with the reenforcing cleats 20 (either metal or wood) suitably secured to the lower sides of the tops, as by screws, except for the trimming strip which is loosely supported by the cleats. The trimming strip 16^a may be easily removed by "backing up" the plugs or screws 30 sufficiently to withdraw the heads of the screws 30 from the outer longitudinal groove in the strip 16^a.

It will be understood that the other section of the box-table may be similar in construction, although paperhangers usually employ the outer longitudinal marginal portion of one section for

trimming and therefore, in order to reduce the cost merely one section need be provided with a removable trimming strip of grainless material; the construction and method of securing the removable trimming strip, if one is employed in both sections, being similar in both instances. The tops of both sections are intended to be disposed in the same horizontal plane when the box-table is in set-up condition and the opened-out box-table may be supported on any suitable independent trestle, it being preferable, however, to have the trestle or supporting standard hingedly secured to the lower side of both sections as exemplified by the angle 29 secured to certain of the cleats 20 with the legs 27 of the trestle or standard hinged at 28 to the angle 29 so as to permit the legs 27 to fold lengthwise beneath the tops and be disposed in the compartment formed by the superposed rails of both sections when the latter are folded back-to-back.

In Figures 5 to 7, I illustrate another modification devised to meet present economical conditions and eliminating the metal cleats.

The box-table, as shown in Figure 5, consists of the two sections 10^a, 11^a of desired width and length. The section 10^a comprises a top 12^a shown glued or otherwise securely fastened on top of the frame rails 32 which are disposed throughout the longitudinal edges and ends of the top 12^a and are of equal vertical depth; while the section 11^a involves a non-movable top portion 33 which terminates a predetermined distance from the outer side rail of the supporting frame of this section. The top portion 33 may consist of plywood or thinner board than the top portion 15 of the table shown in Figure 2 and has its outer longitudinal edge beveled as shown at 34; the top portion 33 being glued or otherwise permanently secured on top of the inner side rail 32 (of the same dimensions as the side rails 32 of section 10^a) and on the end rails which also are similar to those employed for section 10^a.

The outer side rail of this modification is shown as preferably consisting of an inner rail member 35, of less depth than the rails 32, and of an outer rail 36 of somewhat greater depth; the two members being intimately glued or secured together.

The remainder of the top of section 11^a consists of a trimming board or strip 37, of somewhat greater thickness than the top portion 33, and with its longitudinal edges kerfed at an angle, as shown at 38, to correspond with the beveled edge 34 of top portion 33; the kerfs 38 at opposite edges being cut from opposite sides of the board or trimming strip 37 and are made to provide the longitudinal tongues 39.

In view of the added thickness of the strip 37, the two end rails of the frame 32 are cut away or reduced in depth at the outer ends as at 40 to an extent corresponding with the thickness of the tongues 39 of the strip 37, and to the top of the side rail member 35; the cut-outs 40 in both end rails extending from the outer longitudinal edge of the section 11^a to a point slightly beyond the beveled edge 34 of the top portion 33 so as to receive the tongue 39 and thereby lock the inner longitudinal edge of the trimming strip 37 in place. As the other tongue 39 at the outer edge of strip 37 extends from the upper side of the strip, it is made to rest on the outer rail member 36, as shown in Figure 6, while the bottom of the strip 37 rests on the rail member 35.

The outer longitudinal side of strip 37 is shown 75

secured in place by removable screws 41 which pass through the prearranged holes 42 in the comparatively thick rail member 35; the ends of the screws 41 screwing part way into the 5 thick portion of the trimming strip.

In this construction, the trimming strip 37, upon withdrawal of the screws 41, may be easily reversed to present the lower face upwardly after the instant top face has become too scored for 10 further accurate trimming; the reversing of the strip 37 being accomplished by lifting its outer longitudinal edge upwardly as shown in Figure 7.

The two sections 10^a and 11^a of the box-table 15 shown in Figures 5 to 7 are hingedly connected together by a suitable number of hinges 43 which preferably are arranged in grooves cut in the inner or adjacent side rails 32 of the 20 two sections so as to permit the rails of the two sections to be flush with each other when the sections are folded back-to-back.

The exemplifications are believed to be the simplest and best embodiments of the invention, but certain structural modifications may be 25 made, however, without departing from the spirit of the invention as defined in the appended claims.

What I claim is:

1. A paperhanger's folding box-table composed 30 of two sections hingedly connected at their adjacent longitudinal sides to permit folding into back-to-back relation and be disposed in the same horizontal plane when in opened-up condition, the sections comprising top boards and 35 rounding frame forming rails extending beneath the top boards, to which the latter are secured, so that the rails of one section will be superposed on the rails of the other section when in back-to-back relation to provide an implement holding compartment; the top of at least one section involving an immovably secured board at the inner longitudinal side of said section and a reversible self-sustaining trimming strip constituting the outer longitudinal portion of the 40 top of said section, said strip being arranged in the plane of the immovably secured board and both longitudinal edges of said strip having predetermined uniform off-set surfaces adapted to effect interengaging relation with the outer longitudinal edge of the immovable board of said 45 section, the outside rail of said section being formed to engage the outer longitudinal edge of said trimming strip and thereby hold the trimming strip against horizontal movement and in 50 interengaging relation with the immovable board; and adjustable means carried by said outside rail, adapted to engage said trimming strip for removably holding the latter in place against vertical movement.

2. A paperhanger's folding box-table composed 60 of two elongated sections arranged parallel with each other and hingedly connected together at their adjacent longitudinal sides to permit folding into back-to-back relation; a rectangular frame arranged adjacent the edges of each section and extending beneath the tops of the sections whereby the tops of the sections are supported and the frame of one section adapted to be superposed on the frame of the other section 65 when the sections are folded back-to-back to provide an implement holding compartment therebetween; the top of one section involving an immovable portion secured at its inner longitudinal edge and at its ends to the frame and a reversible self-sustaining trimming strip con- 70

stituting the outer longitudinal side of said section and arranged in the same horizontal plane as said immovable portion, both longitudinal edges of said strip having similar recesses adapted to effect interengaging relation with the adjacent longitudinal edge of the immovable portion; the outer longitudinal side frame member of said section being formed to engage the outer longitudinal edge of said strip to hold the latter in interengaging relation with the immovable portion; and screw means carried by said outer side frame member adapted to engage said trimming strip to removably secure the latter in place.

3. A paperhanger's folding box-table composed of two sections hingedly connected together to permit back-to-back folding, the sections consisting of top boards and surrounding frame-rails secured to the edges of the top boards so

as to extend therebeneath to permit the rails of one section to be superposed on the rails of the other section to provide a compartment between the sections, the top of at least one section consisting of an immovably secured board at the hinged side of said section and a self-sustaining reversible trimming strip of grainless material arranged at the outer longitudinal side in the horizontal plane of said section, both longitudinal edges of said strip being provided with similar recesses formed to effect interlocking engagement with the adjacent edge of the immovable board, the ends of said strip being supported by the frame end rails; and adjustable means carried by the outer side rail of said section and adapted to engage in the recess of the adjacent longitudinal edge of said strip to removably secure the latter in place.

FRED E. EDGREN.
